United States Patent Office.

A. B. WOODBURY, OF ASHUELLOT, NEW HAMPSHIRE.

Letters Patent No. 69,149, dated September 24, 1867.

IMPROVEMENT IN JACK-SPINNING MACHINE.

The Schedule referred to in these Letters Patent and making part of the same.

TO ALL PERSONS TO WHOM THESE PRESENTS SHALL COME:

Be it known that I, A. B. WOODBURY, of Ashuelot, in the county of Cheshire, and State of New Hampshire, have made a new and useful invention having reference to the "Jack-Spinning Machine;" and do hereby declare the same to be fully described in the following specification, and represented in the accompanying drawings, of which—

Figure 1 is a top view of a jack-carriage and frame as provided with my invention.

Figure 2 is a transverse section thereof.

The purpose of my invention is to effect the even winding of the yarn upon the spindles while the carriage is being run in from time to time.

To this end I arrange on the carriage A, and at or about at the middle thereof, a hollow post or standard, B, having a slot, *a*, extending through its front side. Within the said standard I place a lifter, C, consisting of a bar, *b*, and an arm, *c*, extending from the upper end of such bar and through the slot. The said bar has a rack or series, *c'*, of teeth applied to one side of it. The arm or projection *c* extends directly underneath the faller or wire *f*, connected to the ends of arms *g g g* projecting from a shaft, *g'*. This faller or wire is arranged in the ordinary manner with respect to the series of spindles and bobbins of the jack-carriage A, two of which bobbins are exhibited at *h h* in the drawings. A spur-gear, *i*, on a horizontal shaft, *k*, engages with the rack *c*, there being a ratchet, *l*, fixed on the said shaft. A lever, *m*, carrying one or more pawls, *n*, to operate the ratchet, and arranged with respect to it in manner as represented in the drawings, is carried in contact with a tripper, *o*, when the carriage is run in, such tripper being extended down from the jack-frame D. This tripper, formed as shown in front view in Figure 3, serves to elevate the longer arm of the lever, and thereby turn the lever on its fulcrum so as to cause its pawl or pawls to act upon and turn the ratchet. This will cause the shaft *k* and the spur-gear *i* to revolve and raise the rack, and of course the faller or wire a short distance. Thus, preparatory to each winding of the yarn upon the bobbins, the faller or wire will be raised a little by the operation of the mechanism, as described, for accomplishing such. This regular elevation of the faller or wire will cause the yarn to be laid evenly on the bobbins. *n'* is the retaining pawl.

I claim, in combination with the jack-carriage and the faller or wire, mechanism, substantially as described, for intermittently raising the faller or wire in order to regulate the laying of the yarns upon the bobbins while the carriage is being run in from time to time.

I also claim the combination, substantially as described, applied to the jack-carriage, faller or wire, and frame for regulating the laying of the yarns upon the bobbins, such consisting of the lifter *c'*, the spur-gear and ratchet, the lever and its pawl or pawls, and the tripper, the whole being applied together and to the carriage and frame, and with respect to the faller or wire, as hereinbefore explained.

A. B. WOODBURY.
